UNITED STATES PATENT OFFICE.

JOHN ARTHUR KEESEY, OF BROOKLYN, NEW YORK.

SIGNALING APPARATUS.

1,262,207.

Specification of Letters Patent.

Patented Apr. 9, 1918.

Application filed December 5, 1916. Serial No. 135,163.

To all whom it may concern:

Be it known that I, JOHN ARTHUR KEESEY, a citizen of the United States, residing at Brooklyn, county of Kings, and State of New York, have invented a new and useful 5 Signaling Apparatus, of which the following is a specification.

The signaling apparatus forming the subject of this invention belongs to that class 10 of mechanically operated signals in which both aural and visual signals are used. When such a system is used as a means of intercommunication between stations or distant places similar signaling apparatus are 15 located at each station, suitably mechanically connected; as applied to ships the places of communication may be the bridge, engine room, the stern and forward part of the vessel, connected up to meet special requirements. The apparatus includes a sound producer, generally a gong, an indicating dial 20 with special orders or messages marked or inscribed thereon, and a pointer adapted to be set at or over any of the orders. The sounding of the gong notifies the receiving 25 attendant an order is being sent, thus calling his attention to the fact that the order is indicated on the dial. The operating parts of the signaling apparatus at the different 30 stations are generally connected together by rods and cables or chains. These transmitting rods, &c., often become slack, from wear and other causes, to such an extent that while the pointer may be moved from one order 35 division of the dial partly over an adjoining order division the gong striking mechanism may fail to act, so, unless the attendant is continuously observing the dial the order will not be immediately noticed, and 40 when noticed the execution of the order may be deleteriously delayed.

The primary object of my present invention is to overcome or eliminate this objectionable feature of existing mechanical signaling systems, and it comprises two or more gong actuating devices, as hammers, and means for successively operating them, whereby one of the hammers will be released from active position to strike the gong as 45 the pointer is fairly set at a signal order and the other hammer or hammers released from active position as the pointer passes between adjacent signal orders; the arrangement being such as to make it practically impossible to move the pointer to or toward 50 an order without giving aural notice that

the signaling apparatus is being manipulated and an order, or change of orders, is impending.

These improvements with others tending 60 to simplify the construction of and insure positiveness of action of mechanical signaling apparatus will now be fully described by reference to the accompanying drawings, in which:

Fig. 1. is a face view of a signaling apparatus embodying my invention.

Fig. 2. a view showing the apparatus with the pointer, dial and gong removed.

Fig. 3. a vertical central section.

Fig. 4. a view of the gong actuating devices, detached, illustrative of the operation of said devices.

Fig. 5. an underneath view of the return signal handle and the manner in which it is 75 connected to an operating chain and pulley, and:

Fig. 6. a side elevation of the plate carrying the teeth for the gong striking hammers.

The kind of signaling apparatus selected for illustrative purposes of this invention is one adapted for use on ships, particularly in the engine rooms, the indicating dial being marked with orders or messages usually 85 sent from the bridge to the engine room, as shown in Fig. 1.

7, designates the indicating dial, 8, the pointer, 9 the return signal handle and 10, its pointer.

Apparatus similar in character and operation are located at the ends of the communicating line, mechanically connected by suitable means. The operating handle of the bridge apparatus actuates the pointer 8, and 95 also sounds a gong, and the handle 9, similarly actuates the pointer of the bridge apparatus.

When the engine attendant receives an order he sets the pointer of the handle 9, at 100 the order indicated on his dial, thus returning the signal to the bridge and notifying the sender that his order is being or has been executed.

The frame consists of a base piece 11, 105 having a circular flange and with lugs by which the apparatus may be secured in operating position, a piece 12, having a circular flange and secured to the base piece 11, by screws 13, leaving a circular space between the flanges, and a bearing 14, provided with spider arms 15, by which it is held, by

screws, on the piece 12. The bearing 14, alines with bearing holes in the centers of the pieces 11 and 12. A gong 16 centrally rests against a shoulder on the bearing 14, and is held thereagainst by the hub 17, of the dial 7; said hub being screw threaded and seated on or near the outer end of the bearing 14. The dial is firmly held in set position by a screw 23, passing through it and into the top of a post 24, projecting from the flanged piece 12.

10 A shaft 18, works in the bearing 14, and the central holes of the pieces 11 and 12, and on this shaft is a pulley 19, preferably 15 formed integral therewith, as shown. A chain 20, is, at its central part secured to the pulley 19, and extends in each direction in the groove of and around the pulley and out of the frame through an opening 21, at its 20 upper part. This chain forms a part of the operating means which connects this apparatus to the operating handle of the signal sending apparatus, and it may be in two parts connected to a block, which by means 25 of a rivet 22, is secured in the groove of the pulley.

Two hammers 25, and 26, on levers 27, and 28, respectively, which have central pivotal bearings on stud 29, extending from the face 30 of the frame piece 12, are by springs 30, 31, connected to the free ends of the lever arms and a bracket 32, caused to strike the gong 16 when the levers are released from their actuating mechanism. On a stud 33, are 35 pivotally held two similarly formed double tappets, comprising a lug 34, or 35, by which they are rocked on the stud, and a short and long sweep arm 36, and 37, or 38, and 39, respectively. These arms extend in two directions from the center of oscillation and act against the short arms of the hammer levers 27, 28, the arrangement being such that said arms under the influence of the springs 30, 31, bear against the sweep arms 40 of the tappets to normally hold the lugs 34, 35, in central position, indicated in Fig. 2. A plate 40, is, by a pin or other suitable means, secured to the shaft 18, between the frame piece 12, and the spider arms 15 of 45 the bearing 14. This plate 40 is provided with two sets of teeth 41, and 42, in different planes, separated by a groove 43, see Fig. 6. The upper or outer set of teeth 41, acts when the plate is rocked in either direction, on the lug 34, of the outer tappet, and the set of teeth 42, similarly acts on the lug 35, of the inner tappet. The teeth 41, and 42, are interspaced, as shown in Fig. 2, so that when a tooth of one of the sets, as a tooth of the 50 set 41, is about to release or drop the lug 34, after tilting the tappet and by its sweep arm 36 has set the hammer lever 27, in backward striking position, a tooth 42, of the other set is about to act, or has partly acted, 55 on the lug 35, of the other tappet, as shown

in Fig. 4. There will be as many teeth in one set as there are changes of orders to be indicated on the dial, and one less in the other set to produce intermediate sound notices. In the particular apparatus shown 70 the number of teeth in the two sets are 8, and 7, respectively. Of course it will be understood that the apparatus may be made to produce more than one intermediate sound signal without departing from the nature 75 of the invention.

As before mentioned the apparatus comprises means for indicating on a similar apparatus at the sending station that an order or message has been received. Said means 80 consists of the handle 9, pointer 10, a grooved pulley 44, which carries or controls a chain 45. Pulley 44, rotates freely on the shaft 18. To insure positiveness of action and prevent disarrangement of parts, as operating handles of apparatus of this character are often submitted to sudden and rough usage, the chain 45, is positively connected to a lug 46, extending from a bracket 47, on and forming a part of the bar 48, of 90 the handle.

This lug enters the groove of the pulley 44, and the bracket extends over the rim of the pulley. A rivet 49, passes through the bracket, the lug and the rim of the pulley. Projecting from the inner end of the bar are ears 50, which extend up the sides of an arm of the pulley and are bent over said arm, as shown in Fig. 5. These parts are thus securely held together, and the 95 function of the pulley is merely to hold and guide the chain 45, the strains on the chain being directly on the handle. Chains 20, and 45, pass from and to their pulleys over guide pulleys 51, and 52, respectively, 105 which are held on short pins or shafts 53, near the opening at the upper part of the frame.

An apparatus of this character if provided with only one set of gong sounding 110 teeth and one double acting tappet, as for instance the set of teeth 42, and tappet 35, 38, 39, is liable to miss giving an aural signal when the connections between coöperating apparatus, comprising connecting rods 115 and the chains 20, and 45, become slack or relaxed. Under such conditions while the pointer 8, may be moved over a dividing line of adjacent orders it may often not be moved full normal signaling distance. As 120 for instance the pointer may be moved over a space indicated by the dotted lines *x* and *y*, Fig. 1, the tappet will not be moved a distance adequately to sound the gong. The intermediate teeth of the set 41, with its 125 coacting tappet 34, 36, 37, and the extra hammer 25, will positively insure that an aural signal is given under such conditions.

I claim:

1. A signaling apparatus, comprising a 130

- gong, an order or message indicating dial, a pointer therefor, two gong striking hammers, a controller for each hammer, a plate provided with teeth formed and arranged to 5 similarly alternately actuate the controllers of the hammers in both directions of movement of the plate, and a shaft to which the pointer and plate are connected, whereby as the pointer is moved in either direction from 10 any message to an adjoining one both hammers are caused to strike the gong.
2. A signaling apparatus, comprising a gong, an order or message indicating dial, a pointer therefor, two gong striking hammers, a plate provided with teeth arranged 15 in two sets in different planes adapted to alternately actuate the hammers as the pointer moves from one order to another, and a shaft to which the pointer and plate 20 are connected.
3. A signaling apparatus, comprising a gong, an order or message indicating dial, a pointer therefor, two gong striking hammers, a stud bearing on which the hammers 25 rock, a double acting tappet for each hammer, a plate provided with teeth arranged to alternately actuate the tappets in both directions of movement of the plate, a spring connected to and for throwing each hammer against the gong, and a shaft to which 30 the pointer and plate are connected.
4. A signaling apparatus, comprising a gong, an order or message indicating dial, a pointer therefor, two gong striking hammers, a plate provided with teeth arranged 35 in two sets in different planes adapted to alternately actuate the hammers, one set containing as many teeth as there are changes of orders to be indicated on the dial and the other one having one less tooth, a spring connected to and for 40 throwing each hammer against the gong, and a shaft to which the pointer and plate are connected, whereby as the pointer is moved in both directions from an order to 45 an adjacent one on the dial both hammers will be actuated.
5. A signaling apparatus, comprising an order or message indicating dial, a pointer therefor, means for setting the pointer at any selected order, a signal operating handle 50 provided with a pointer adapted to be set at any of the orders on the indicating dial, a grooved pulley to which the bar of the handle is attached, a bracket extending from said bar and provided with a lug seated in the groove of the pulley, a chain connected to the lug and extending in both directions 55 therefrom in the groove of the pulley and means for securing the handle bar to an arm of the pulley.
- Signed at New York, county and State of New York, November, 1916.
